UNITED STATES PATENT OFFICE.

WILLIAM A. JENKINS, OF WILMINGTON, CALIFORNIA.

THREAD-CUTTING DIE.

Application filed June 29, 1925. Serial No. 40,244.

The present invention relates to thread cutting dies and has for its principal objects, the provision of a long-lived, efficient die which may be used in automatic thread cutting machines or in lathes and the like, as well as on stocks.

Another object of the invention is to provide a die which may be repeatedly sharpened with ease and without exercise of particular skill.

In present types of dies, the die, when cutting a thread, has all possible cutting edges and surfaces in contact with the metal being worked. Therefore, the wear on such a die is distributed throughout all the threads of the die, and after such a die has worn to any appreciable degree the only change or repair that can be made is to contract the die, provided it is the adjustable type. If the character or contour of the threads change through wear or otherwise, there is nothing practical that can be done to alter same.

It is therefore another object of the invention to provide a die in which all of the cutting threads thereof are not used at the same time, or in other words, to provide a die in which a large area is given to threads, the major portion of which are kept in reserve until preceding portions have worn sufficiently to be unfitted for use.

Another object of the invention is to provide a die of the above character which is designed to provide the correct type of throat and to give the required chip clearance.

Still other objects and advantages of my invention will appear hereinafter.

I have illustrated my invention by the accompanying drawings in which:

Fig. 1 is a vertical section of a nipple threading machine to which one embodiment of my invention is applied.

Fig. 2 is a face view thereof.

Fig. 3 is an enlarged detail section on a line 3-3 of Fig. 1.

Fig. 4 is a perspective of a die member constructed in conformance with the invention, said die member being adapted for use singly or in multiples as shown in Figs. 1 and 2.

Said die member, indicated throughout the drawings by the numeral 6, is made of a single circular blank or disc of suitable metal, from which disc a portion of the metal is cut away, as at 7. The portion cut away

is segmental. The remaining part of the disc, in the embodiment illustrated, is more than 180° of a circle, but it will be apparent hereinafter that either a comparatively small segment, or a large segment may be cut away. If the removed portion is in excess of 180° of a circle, the die member will have a segmental appearance, therefore it may be said of the die member, that it is of circular disc form with a segmental portion removed, and it may also be referred to as being segmental in itself.

In any case, said member is distinguished by an arcuate threaded perimeter 8 described around a given point. In the embodiment shown, said point is represented by a central aperture, the threaded perimeter being coaxial of the aperture. Said member is further distinguished by an inwardly extending surface 9 intersecting the threaded perimeter at a suitable angle to provide suitable cutting edges 10 by virtue of the abrupt terminations of the threads on said perimeter. The best angle of such intersection is believed to be about 90°, in which the said surface is truly radial of the perimeter. Such angle of intersection provides maximum strength with the best possible chip clearance consistent with strength, and it will be apparent hereinafter that greater chip clearance is provided by my invention, than is obtained in usual types of thread cutting dies.

The die member illustrated is designed for cutting pipe threads or other taper threads, and the complete embodiment shown is particularly suited for threading pipe nipples and the like. However, the invention is obviously applicable to straight-thread cutting purposes. The die is shown as provided with the usual throat 12, the threads increasing in fullness rearwardly from the throat in conformance with accepted practice.

The parts of the machine shown in Figs. 1 and 2 include a spindle 13 and a face plate 14, which may be properly associated with the spindle by suitable feeding and backing-off mechanisms (not shown). The plate is provided with radially disposed slots 15. Said face plate includes a circumferential, rearwardly extending wall or flange 16, carrying a plurality of studs 17 projecting radially inward and aligned with corresponding slots. Said studs are revolvably held to the wall 16 by means of integral collars 18; a

smooth portion 19 of the stud being a revolving fit in a drilled hole 20 provided in said wall.

Associated with each stud, there is a plate 21 disposed behind a corresponding slot. Said plate may be moved inwardly and outwardly radially of the face plate by proper turning movement of the stud. Each one of plates 21 is provided with a central aperture 22 aligned with the slot and through which a hollow internally threaded bolt 23 is extended. The end of each bolt extends beyond the outer surface of the face plate.

Over each of the radial slots, one of the die members is disposed. The die member is held securely contiguous with the face plate by means of bolt 24 screw-threaded into the hollow bolt 23. The central aperture of each die member is bounded by a serrated or roughened surface 25 which increases in diameter inwardly and is adapted to receive a conical washer 26. The bolt 24 passes through the washer, and by tightening said bolt, the corresponding die member is held to the face plate. The conical washer is of course not revolvable in the die member, but said washer is revolvable around the hollow bolt, so that the die member is revolvably adjustable around said bolt.

The face plate, with a plurality of die members arranged thereon in an annular series, as shown, may be termed a complete multi-cutting-edged die. The points represented on each die member by the intersection of the perimeter with the surface 9, are disposed an equal distance from the center of rotation of the face plate, so that the embodiment illustrated, for example, the complete nipple-threading die is possessed of four cutting edges.

In the operation of the complete die, each die member touches metal at extreme cutting edge only, the remainder of the threaded perimeter curving rearwardly and away from the work to provide an ideal chip clearance or space indicated by the numeral 28. When the cutting edge of a die member becomes worn, or the threads at the cutting edge break or become otherwise unfitted, the surface 9 is placed against a grinding wheel

(not shown) and said surface is ground down until a new and untouched portion of the perimeter is in intersection with the surface 9. Thus, the dies are constantly renewable, and a die such as shown in Fig. 2, will last many times longer than if all parts of the threads were simultaneously used, as in the case of annular dies in which the threads are cut on an inside perimeter. The die members are easily manufactured by setting the blank in a lathe or the like, turning the threads and throat, and grinding the surface 9.

While I have shown and described a specific embodiment of my invention I do not limit myself to any specific construction or arrangement of parts and may alter the parts and the construction and arrangement thereof, as I desire, without enlarging the scope of my invention, within the appended claim.

I claim as my invention:

The combination with a plate provided with a centrally arranged opening and a series of radially disposed slots between said opening and the edge of said plate, radially adjustable blocks arranged on the rear face of said plate, which blocks overlie the radial slots, a bolt carried by each block and projecting through the corresponding radial slot, a disk-shaped thread cutting die positioned on the front face of the plate over each radial opening therein, a portion of the periphery of each die being cut away so as to provide a radially disposed surface that intersects at right angles the threaded surface of the disk, the radially disposed surfaces of all the disks projecting inwardly from the marginal edge of the opening in the plate, there being an aperture formed in the center of each disk the inner portion of which aperture is countersunk and corrugated, a retaining disk positioned in the aperture of each die, the edge of which disk is inclined and corrugated so as to engage the countersunk corrugated inner portion of the aperture, and means for securing each retaining disk to the end of the corresponding bolt.

In testimony whereof I affix my signature:

WILLIAM A. JENKINS.
